Radio Corporation of America, a corporation of
Delaware

Application January 20, 1943, Serial No. 472,952

6 Claims. (Cl. 178—69.5)

This invention relates to an improvement in impulse mixer circuits, and more specifically to an improvement in a circuit arrangement for mixing impulses in a television system where the impulses correspond to the horizontal and vertical deflection frequencies.

In the transmission of television signals, as is well known to those skilled in the art, some means must be provided for maintaining synchronous operation of the various receivers with the transmitter. This is accomplished by transmitting a series of synchronizing impulses which, when received at the television receiving apparatus, are effective to maintain the desired degree of synchronism. In order that the necessary degree of synchronism may be maintained, it is desirable to transmit a synchronizing impulse corresponding to each line scanned, and a further synchronizing impulse corresponding to each field scanned. The line scanning rate and/or the field scanning rate may be altered to suit particular circumstances, but in any event, synchronizing impulses of relatively short duration are generally transmitted corresponding to each of these parameters.

In the conventional transmission of television signals, the line synchronizing impulses are transmitted during the interval between picture signals representative of each line, and the field synchronizing impulses are transmitted during the interval between picture signals representative of each field. In an electronic television system, these synchronizing signals initiate the horizontal and vertical return of the cathode ray beam.

In television transmitting systems, impulses of both line and field frequencies are also used to blank or obliterate picture signals which may be produced during the return deflection of the scanning cathode ray beam or, as an alternative, impulses of line and field frequencies may be used to interrupt the scanning cathode ray beam or its discharge action in the television pickup tube in order that no picture signals will be generated during the cathode ray beam return time. For the purpose of providing blanking potentials, and for other purposes in a television transmitter or receiver, it becomes necessary to mix or combine two series of impulses, one repeating at line deflection frequency and the other repeating at field deflection frequency. The individual impulses of the two series are generally of different time duration.

In most television transmitting systems, an impulse generating system is provided which produces impulses of line and field frequency in order that a definite relationship may be maintained between the frequencies of the two series of impulses, and through the use of frequency divider circuits, the line and field series of impulses may be derived from different parts of the impulse generating system. When these impulses are applied to an impulse mixing or combining circuit, they are combined so that the produced series of impulses will represent a composite of both the line and field impulse series.

Various mixer circuits have heretofore been used, but frequently such circuits are not of optimum desirability in that they do not produce the desired wave form in a composite impulse series, or they may require an excessive input voltage to produce the desired final wave form. Furthermore, presently known impulse mixing circuits are somewhat complex and include a great number of tube elements and parts. In the present invention, an impulse mixing circuit has been provided which is simple in operation and which will produce a desired composite wave form by the application of a relatively low intensity controlling impulse series.

One purpose of the present invention, therefore, resides in the provision of an impulse mixing circuit which is simple in operation, and which embodies the use of a limited number of tube and circuit elements.

Another purpose of the present invention resides in the provision of an impulse mixing circuit wherein it is possible to produce a desired composite wave form, the impulse mixing circuit being initiated by relatively low intensity impulses of line and field frequency.

A still further purpose of the present invention resides in the provision of an impulse mixer circuit in which tilted or peaked impulses may be applied to the mixer circuit without affecting the wave form of the composite series of impulses.

Still other purposes and advantages of the present invention will become more apparent to those skilled in the art from the following detailed description, especially when considered in connection with the drawing, wherein the single figure represents a preferred form of the present invention.

Referring now to the drawing, there is shown an electron discharge tube 10 which includes two separate electron streams. These electron

streams or paths may be enclosed within the same tube envelope or, as will be appreciated, two separate tube envelopes may be used.

One of the electron streams or paths includes a cathode 12, a control electrode 14 and an anode 16. The other electron path includes a cathode 18, a control electrode 20 and an anode 22. The cathode 12 of the first electron path is connected to ground or to a point of constant or fixed potential, while the anode 16 is connected to the positive terminal 24 of a source of energy (not shown) by way of anode resistance 26. The control electrode 14 is maintained at a potential slightly positive with respect to the cathode 12 by means of a potential divider including resistances 28 and 30 which are connected in series between the positive terminal 24 and the negative terminal or ground. The control electrode 14 is connected to the junction of these resistances, and the potential of the control electrode 14 with respect to the cathode 12 may be determined by properly proportioning the value of the resistances.

The cathode 18 of the second electron path is connected to ground by way of cathode resistance 32, while the anode 22 is connected to the positive terminal 24 by means of the anode load resistance 34. A potential divider including series resistances 36 and 38 is connected between the positive terminal 24 and the negative terminal or ground, while the control electrode 20 is connected to the junction of these resistances. The potential of the control electrode 20 relative to ground may, therefore, be controlled by proportioning the resistances 36 and 38. The anode 16 of the first electron path is connected to the cathode 18 of the second electron path by means of a coupling condenser 40.

Impulses of horizontal or line deflection frequency are applied to the input terminals 42 and 44, these terminals being connected respectively to the control electrode 14 of the first electron path and to ground. The horizontal impulses may have a wave form such as indicated at 46, the frequency of the impulses corresponding to the line deflection frequency. When impulses of such a wave form are applied to the control electrode 14, a potential variation is available at the anode 16 similar to the wave form shown at 48. The bias of the control electrode 14 relative to the cathode 12 is such that the first electron path performs a clipping action on the applied impulses with the result that the impulse peak is removed. Naturally, the polarity of the impulses is reversed due to the phase inversion operation of the tube. These impulses, as represented at 48, are then applied to the cathode 18 of the second electron path to modulate the cathode potential relative to ground.

Impulses of vertical or field deflection frequency are applied to the terminals 50 and 52 which are connected respectively to the control electrode 20 and to ground. These impulses extend in a negative direction as to the applied horizontal impulses, and the vertical impulse series may be peaked by reason of the action of the vertical impulse generator or multi-vibrator. When impulses of vertical deflection frequency are applied to the control electrode 20 of the second electron path, the control electrode 20 is driven sufficiently negative to block the tube to preclude the passage of current to anode 22. The impulses of line deflection frequency as represented at 48 which are applied to the cathode

18 are also of sufficient intensity to cause the tube to be blocked by driving the cathode 18 positive. Current through the second electron path is, therefore, interrupted both during the application of impulses of line frequency to the cathode 18, and during the application of field impulses to the control electrode 20. Modulation of the electron stream in the second electron path, therefore, varies the amount of current in the anode circuit with the result that a potential variation may be derived from the anode 22 which is representative of the combined series of impulses. This potential variation may be derived from output terminals 56 and 58, the former being connected to the anode 22 by way of a relatively large condenser 60, while the terminal 58 is connected to ground or some point of fixed potential. The output terminals 56 and 58 are connected together by a variable resistance 62 of a relatively low value.

In order that the second electron path including cathode 18 and anode 22 may be driven to cut-off by cathode modulation, the anode resistance 34 is made relatively large in order to reduce the plate voltage at the anode 22 in order that the impulses of line frequency as applied to the cathode 18 may produce a sharp cut-off of the current flow through the tube. As previously stated, the electron path is also driven to cut-off by the impulses of vertical or field deflection frequency, and the cut-off potential is represented, for example, by the dotted line 55 associated with the wave form curve 54. The composite or mixed impulses which are available from the anode 22 of the second electron stream are, therefore, positive in polarity and are preferably derived by way of a relatively low alternating current load in order to maintain good wave form. The low impedance alternating current load is produced by means of the relatively large condenser 60 and the relatively small resistance 62.

In order that proper direct current potentials may be applied to the control electrodes 14 and 20, the resistance 30 is generally chosen to equal approximately 10% of the value of resistance 28, while the resistance 38 is generally chosen to equal approximately 5% of the resistance 36. The cathode resistance 32 may have a value of approximately 500 to 1,000 ohms while the anode resistance 26 for the first electron path may have a value from 15,000 to 50,000 ohms. As explained above, in order to produce a sharp cut-off in the second electron path, the anode resistance 34 should preferably have a fairly high value corresponding to approximately 200,000 ohms.

For performing the combining or mixing operation, the tube 10 may be of the type 6SL7-GT or type 7F7, although it is to be understood that various other single or dual purpose tubes may be used where desired.

The base line of the mixed impulses, as represented by the wave form 64 and available from the output terminals 56-58, can be made perfectly flat or it may be tilted to a desired degree for one or both of the input impulse series by pre-tilting the base line of the wave forms supplied to either of the control electrodes 14 or 20. Such pre-tilting may be used, for example, to compensate for errors introduced by the time constants of the coupling circuits, and if pre-tilting is employed, the time constants may be given smaller values.

It will be observed from an inspection of curve 46 that the horizontal impulses as applied to the input terminals 42 and 44 extend in a negative direction. If, however, the available impulses

of horizontal deflection frequency should extend in a positive direction, a similar mixing circuit could be used by providing cathode coupling between the two triode sections of the tube 10. If horizontal impulses of such polarity are applied to the input terminal 42, it would still be desirable to apply positive impulses of horizontal deflection frequency to the cathode 18 of the triode section including cathode 18, control electrode 20 and anode 22. In this case, the coupling condenser 40 would be omitted and the cathode 12 would be directly connected to the cathode 18 in order to afford the desired cathode coupling. The cathode resistance 32 would then be common to both cathode electrodes.

With such a slight revision it would then be possible to apply horizontal impulses having a polarity reversed with respect to those shown in the figure, and still utilize the present invention for affording a circuit arrangement for mixing the horizontal and vertical impulses. The same tube types as suggested above could be used, or, if desirable, a tube such as the type 6SC7 could be employed since this particular tube type has a common cathode electrode.

Furthermore, it is conceivable that the application of the horizontal and vertical impulses to the cathode 18 and control electrode 20 could be reversed, assuming, of course, that the polarity of the impulses is simultaneously reversed. Under these conditions, vertical impulses that extend in a positive direction could be applied to the cathode 18, and horizontal impulses extending in a negative direction could be applied to the control electrode 20. These latter impulses would be derived from anode 16 by way of condenser 40 and would result from the application of horizontal impulses to the control electrode 14, the pulses extending in a positive direction. It is desirable that the polarity of the applied pulses operate to bias the control electrode 20 with respect to the cathode 18 such that electron flow to the anode 22 is precluded.

In the present invention, the duration of the individual horizontal impulses corresponds to about 7% to 8% of the horizontal deflection interval, and the duration of the vertical impulses corresponds to about 1.0 or 1.5 horizontal deflection cycles. It is to be understood, however, that impulses of different time duration could as well be used in the present invention.

Through the use of the present invention it may, therefore, be seen that an effective and efficient impulse mixing or combining circuit has been provided which will respond to applied impulses of relatively low intensity, and which will produce the desired composite wave form even though some tilting or peaking may be present in the applied impulses. Furthermore, it will be appreciated that all of the impulses of the composite series as represented by the curve 64 have the same intensity, their duration and frequency being determined by the duration and frequency of the applied horizontal and vertical impulse series. It will also be appreciated that an impulse mixer circuit has been provided which will produce a composite series of impulses without in any way affecting the operation or action of the sources from which the independent series of horizontal and vertical impulses are derived.

Although the present invention has been described somewhat in detail, it will be appreciated that various alterations and modifications may be made therein without departing from the spirit

and scope thereof, and it is desired that any and all such alterations and modifications be considered within the purview of this invention except as limited by the hereinafter appended claims.

Having now described my invention, what I claim as new and desire to have protected by Letters Patent is:

1. An impulse mixer for combining two series of impulses, the impulses of each series differing in time duration and frequency, comprising a first and second electron discharge path each including a cathode, a control electrode, and an anode, an anode load impedance associated with each electron discharge path, means for applying the impulses of one of the series to the control electrode of the first electron discharge path to produce voltage variations of corresponding time duration and frequency across the load impedance of that path, 10 means including a coupling condenser for applying the voltage variations produced across the load impedance of the first electron discharge path to the cathode of the second electron discharge path, means for applying the other series 15 of impulses to the control electrode of the second electron discharge path whereby the impedance of the second electron discharge path will be altered by both the applied produced voltage variations and the other applied series of impulses, 20 and an output circuit coupled across the anode load impedance of the second electron discharge path.

2. An impulse mixer circuit for combining two series of impulses comprising a first and second 35 electron discharge path each including a cathode, a control electrode and an anode, an anode load impedance associated with each electron discharge path, means for applying the impulses of one of the series to the control electrode of the first electron discharge path to thereby produce corresponding voltage variations at the anode of that path, means for applying the voltage variations produced at the anode of the first electron 40 discharge path and the other series of impulses to the cathode and control electrode of the second electron discharge path to produce a series of voltage variations corresponding to the combined series of impulses, and an output circuit associated with the second electron discharge path.

3. An impulse mixer circuit for combining two 55 series of impulses, the impulses of each series differing in time duration and frequency, comprising a first and second electron discharge path each including a cathode, a control electrode and an anode, means to apply the impulses of one of the series to the control electrode of the first electron discharge path to thereby produce voltage variations of corresponding time duration and frequency across an anode load circuit associated with the path, and means to apply the voltage variations produced across the anode load circuit and the other series of impulses to the cathode and control electrode, respectively, of the second electron 60 discharge path thereby to produce a composite series of voltage variations corresponding to the combined series of impulses in an output circuit associated with the second electron discharge path.

4. An impulse mixer circuit for combining a series of impulses of one frequency with a series of impulses of another frequency comprising a first and second electron current path each including a cathode, a control electrode and an

anode, means for applying the impulses of said one frequency to the control electrode of the first electron current path to produce voltage variations of a corresponding frequency at the anode of that electron current path, means for applying the voltage variations produced at the anode of the first electron discharge path to the cathode of the second electron current path, means for applying the impulses of said another frequency to the control electrode of the second electron current path, the applied produced voltage variations and the applied impulses of said another frequency operating to modulate the current intensity in the second electron current path to produce voltage variations corresponding to both series of impulses at the anode of the second electron current path, and an output terminal connected to the anode of said second electron current path.

5. An impulse mixer circuit for combining a series of impulses of one frequency with a series of impulses of another frequency comprising a first and second electron discharge path each having a cathode, a control electrode and an output electrode, means for applying the impulses of the one frequency to the control electrode of the first electron discharge path to produce corresponding potential variations at the output electrode of that electron discharge path, means for applying the potential variations produced at the output electrode of the first electron discharge path to the cathode of the second electron discharge path, and means for applying the volt-

age variations of the other frequency to the control electrode of the second electron discharge path, the applied produced potential variations and the applied impulses of the other frequency being effective to modulate the electron stream in the second electron discharge path to produce voltage variations representative of the combined impulses of both frequencies at the output electrode of the second electron discharge path.

10 6. An impulse mixer circuit for use in a television system for combining a series of impulses of line frequency with a series of impulses of field frequency comprising a first and second electron discharge path each including a cathode, a control electrode and an anode, means to apply impulses of line frequency to the control electrode of the first electron discharge path to produce corresponding voltage variations at the anode of that electron discharge path, means to apply the voltage variations produced at the anode of the first electron discharge path to the cathode of the second electron discharge path, means to apply the impulses of field frequency to the control electrode of the second electron discharge path, the applied produced voltage variations and the applied impulses of field frequency operating to modulate the electron stream in the second electron discharge path to produce voltage variations representative of both line and field frequency at the anode of the second electron discharge path, and an output terminal connected to the anode of said second electron discharge path.

OTTO H. SCHADE.
